N. D. HUGHES.

NURSERY CHAIR.

APPLICATION FILED MAY 28, 1918.

1,291,898.

Patented Jan. 21, 1919.

UNITED STATES PATENT OFFICE.

NAOMI D. HUGHES, OF PRINEVILLE, OREGON.

NURSERY-CHAIR.

1,291,898.

Specification of Letters Patent. Patented Jan. 21, 1919.

Application filed May 28, 1918. Serial No. 237,067.

To all whom it may concern:

Be it known that I, NAOMI D. HUGHES, a citizen of the United States, residing at Prineville, in the county of Crook and State 5 of Oregon, have invented certain new and useful Improvements in Nursery-Chairs, of which the following is a specification.

This invention relates to improvements in nursery chairs and it is the principal object 10 of the invention to provide a foldable nursery chair which, when not in use can be folded into compact form and placed in a convenient or limited space thus rendering the same exceedingly desirable for use in 15 traveling or in apartments and like places.

Other objects will be in part obvious and in part pointed out hereinafter.

In order that the invention and the manner of its application may be readily understood, I have in the accompanying illustrative drawings and in the detailed following description based thereon set forth a preferred embodiment of the invention.

In these drawings:

25 Figure 1 is a perspective view of the improved chair,

Fig. 2 is a rear elevation thereof, and

Fig. 3 is a fragmentary detail in top plan showing the connection of the rear leg of 30 the chair with the seat of the same.

Having more particular reference to the drawings, in connection with which like reference characters will designate corresponding parts throughout the several views, 1 35 represents the seat of the improved chair having legs 2 and 3 pivoted to the forward marginal portions thereof as at 4 and adapted to bear against stops or strips 5 secured to the under side of the forward portion 40 of the seat and extending for a distance beyond the marginal portions thereof, as clearly shown in Fig. 1. In this way, it is to be noted that the legs 2 and 3 will be braced in their set-up positions, consequently, affording an effectual support for the forward portion of said seat 1. Secured to the rear marginal portion of the seat, preferably intermediate its ends, is another leg 6, the same being pivoted to said seat as 45 at 7, and adapted to swing at substantially right angles to the path of movement of the 50

legs 2 and 3; a hook 8 being loosely connected to the intermediate portion of the leg as at 9 and adapted to be engaged with an eyelet 10 carried on the adjacent marginal portion of the seat 1 whereby to hold the leg 6 in its set-up position, thus, preventing collapsing of the chair when in use. Attention is directed to the fact that by arranging the forward legs 2 and 3 at an incline, as clearly 60 shown in the Fig. 1, I am enabled to produce a rigid and substantial support. 55

To brace the upper portion of the rear leg 6 when in its set-up position, a stop 11 is secured to the rear marginal portion of 65 the seat and as will be noted, is shouldered as at 12 and adapted to receive the adjacent portion of said leg thereon.

Manifestly, the construction shown is capable of considerable modification and 70 such modification as is within the scope of my claims, I consider within the spirit of my invention.

I claim:

1. A nursery chair including a seat, legs 75 pivoted to the marginal portions thereof and adapted to be moved in directions at substantial right angles to each other, stops carried by the seat adjacent the legs adapted to be engaged thereby, and a hook carried 80 by one of said legs engageable with the adjacent portion of the seat for maintaining the same in upright position.

2. A nursery chair including a seat, legs pivoted to the marginal side portions there- 85 of at points adjacent the front of the seat, stops arranged on the side marginal portions adjacent the legs adapted to be en- gaged thereby, another leg pivoted to the rear marginal portion of the seat interme- 90 diate the side marginal portion thereof adapted to be moved at substantially right angles to said first legs, a stop engaged with the rear marginal portion for limiting move- 95 ment of said last leg, and a hook carried by the last leg engageable with the rear marginal portion of the seat for maintaining the same in upright position.

In testimony whereof, I affix my signature hereto.

NAOMI D. HUGHES.
